UNITED STATES PATENT OFFICE.

FRANCIS M. SIMONDS, OF NEW YORK, N. Y., ASSIGNOR OF ONE-HALF TO A. FILLMORE HYDE, OF NEW YORK, N. Y.

ORE FURNACE.

Application filed February 19, 1925. Serial No. 19,164.

The present invention relates to a method of treating ores of all kinds and to a form of furnace for carrying out that method. This furnace and the method of its operation affords a high degree of flexibility and adaptiveness, making it possible to subject a given ore to a continuous total treatment involving a great variety of changes in successive partial treatments, and all within 10 the same furnace and perfect control available for each partial process separately.

The process involves the novel plan of causing the active gases to pass through a thin sheet of the broken ore, and more especially during forward movement of the sheet through the furnace.

This invention is particularly well suited to the treatment of ores in accordance with the process described in my pending U. S. 20 patent application Serial No. 5159, filed January 27th, 1925, although the invention is by no means confined to carrying out said process of treatment.

A preferred form of the invention is illustrated in the accompanying drawings where-in Figure 1 is a central vertical section of the furnace on the plane 1—1 in Figure 3, Figure 2 is a similar section on the plane 2—2 in Figure 3, Figure 3 is a horizontal 30 sectional view of the furnace, and Figure 4 is a partial vertical section of one of the furnace walls, shown on a larger scale.

The furnace as herein shown in circular in cross section and the descending ore mass is annular in cross section. This preferred form is not essential, as a furnace and ore mass of polygonal cross section is within the invention.

The mass of crushed ore is charged upon 40 a cone 10, and descends in the form of a hollow cylindrical sheet or shell 11, say two or three inches thick (these dimensions not being essential) which increases gradually in thickness toward the bottom as shown in Figure 2, to facilitate the movement of the ore. The material is finally received in a hopper 12, whence it may be removed by any appropriate means, as for instance, the screw conveyer 13.

45 The descending ore is confined between interior and exterior cylindrical walls 14 and 15, the nature of which is hereinafter described in connection with Figure 4. The interior wall forms the periphery of a long vertical cylinder which is made up of super-

posed sections or cylindrical distribution chambers. These are separated by horizontal walls or floors 16, and as shown in the drawing, there are eight of these distribution chambers. Any desired and convenient 50 number of such chambers may be used.

The walls and floors of these chambers are made of fire clay, sheet steel, or other appropriate material, and a firm vertical support is afforded for the entire interior structure by hollow columns formed from sections 17 in each chamber. Each sectional column in each chamber stands exactly over a similar column in the chamber beneath it. The entire section of the furnace can thus 70 be built up of separate removable units of suitable dimensions for the particular purpose desired, which can be replaced separately whenever found expedient.

The function of each of these chambers is to distribute laterally fine streams of more or less active (or if necessary inert) gases of various kinds to the descending sheet of ore mass through appropriate perforations. These heated gases are supplied preferably 80 on opposite sides from inlet passages 18 registering with entrance openings 19 in the respective chambers. As shown in Figure 3, the inlet passages necessarily extend across and interrupt the sheet of ore mass on each side. These gases, whether reducing or oxidizing or of any chemical character, are supplied from any suitable source (not shown) through entrance 20.

In the particular form of apparatus herein shown, the gas (whether pre-heated or not) is mixed with air and burned just as it is entering the openings 20. For this purpose a pipe 20^a is used which may supply air or gas, the gas or air for burning coming 90 in around said pipe 20^a. The flame is preferably projected against a fire clay pillar 20^b to promote complete combustion, in a well known manner.

The gases may either be heated before admission to the distributing chambers or means may be provided for heating them within the furnace. In either case they pass outward from each chamber through perforations 21 (see Figure 4) and, after traversing the ore mass 11, they are discharged through perforations 22 in the outer cylindrical wall 15 (preferably of sheet metal) into the space 23, which surrounds the exterior wall 15.

The perforations 21 preferably extend downward and outward, say at an angle of 45 degrees to prevent any ore from falling into the interior chambers. I prefer to supply means for filtering the outgoing gases as they enter the chamber 23, and for this purpose I may use a layer 24 of asbestos or the like, held in place by wire mesh 25. Other filtering means may be used.

10 The gas, after passing through the ore mass into the chamber 23 is led off by branch pipes 26 into main outlet pipes 27, and the movement of this gas can be promoted and increased by any forcing means, as, for instance, suction fans applied to the pipes 27. In such cases it may be desirable that some of the gases used be segregated, either for the collection of by-products, as for instance sulphur, or to be returned to the furnace or 20 used in another furnace to be burned or be otherwise utilized. This may, of course, be done by supplying the necessary separate pipes for separate gas collection from one or more distributing chambers.

25 It will be seen that the nature of the treatment of the ore body as it passes down by each distributing chamber in succession is determined by the nature and temperature of the gases supplied to it from the respective chambers. This can, of course, be separately controlled in a well known manner for each chamber separately, and the ore can thus be given any desired partial treatments on its way through the furnace. The duration of each partial treatment will depend upon the vertical height of each chamber.

As shown in the drawings the chambers are made each higher than the one above it, but it is to be understood that this is merely one 40 example of the possible arrangement of different vertical heights of the chambers. Any arrangement and relation suitable to the particular process intended to be carried out may be employed without departing from 45 my invention.

In order to make certain the gradual downward movement of the ore and to prevent packing, clogging or sticking either locally or otherwise, it may become necessary to impart a certain degree of agitation from without. As an example of a preferred means to this end I have shown the line of pillars 17 supported by a common support 28, which is carried upon the vertically movable member of a hydraulic ram, indicated at 29. By causing this movable member to make slow periodic up and down movements through a short distance, the entire vertical series of distributing chambers can be given a slow up and down move-

ment which will prevent all stoppage in the progress of the ore mass under treatment. As this is a very slow movement through a relatively short vertical path, it will not interfere with the operation of the furnace 65 in any way.

It will be seen that the operation of this form of furnace involves the treatment of the ore by arranging the mass in a relatively thin layer, and passing the gaseous reagents 70 through this layer transversely. This insures a high degree of activity and efficiency, as it brings every particle of the ore into contact with the gases used and as every particle of gas within each distributing chamber is obliged to pass through the ore mass before it can leave the furnace.

Furthermore, by causing the layer of ore to move past a series of gas distributors, this efficient reaction may be made available for 80 almost any number of successive treatments of different kinds, each treatment being of a suitable duration and each being independently controllable.

It is to be understood that the process 85 herein described may be carried out by other means than those herein described and claimed, without departing from my invention, and also that many changes may be made in the apparatus described and claimed 90 within the scope of the invention, which is not limited to the details herein shown and described.

What I claim is—

1. In an ore treating furnace, a number of separate distributing chambers arranged in a vertical series and having perforated peripheral walls, means for supplying different qualities of gas to the various distributing chambers, a second perforated ore confining wall surrounding the distributing chambers to form a space for descending ore, and means for conveying gases away from said second wall.

2. Apparatus as in claim 1 in combination with means for imparting a vertical movement to the distributing chambers to promote certain movement of the ore.

3. Apparatus as in claim 1 wherein the distributing chambers are of different 110 heights.

4. Apparatus as in claim 1 wherein separate spaces are provided behind the second perforated wall corresponding respectively to the various distributing chambers, together with independent means for conveying gases from each of said separate spaces.

In testimony whereof I have hereto affixed my signature.

F. M. SIMONDS.
